HAND POWER TOOL

David C. McElroy, St. Clair Shores, Mich., assignor to
Thor Power Tool Company, Aurora, Ill.

Filed July 20, 1970, Ser. No. 24,032

Term of patent 14 years

Int. Cl. D8—05

U.S. Cl. D8—68

FIG. 1 is a top perspective view of a hand power tool embodying my new design;

FIG. 2 is a back elevational view thereof;

FIG. 3 is a front elevational view thereof;

FIG. 4 is a side elevational view thereof showing the side not seen in FIG. 1; and

FIG. 5 is a top plan view thereof.

I claim:

The ornamental design for a hand power tool, substantially as shown.
